CLAIM

The ornamental design for night vision goggles as shown and described.

DESCRIPTION

FIG. 1 is a front, right, and top perspective view of night vision goggles showing my new design;

FIG. 2 is a rear, left, and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged portion view taken from encircled portion “9”, in FIG. 2.

The even dash broken lines in the drawings depict portions of the night vision goggles that form no part of the claimed design. The dot-dash broken lines in the drawings demarcate the boundaries of the enlarged views and form no part of the claimed design.
